United States Patent

Des. 240,376
Patented July 6, 1976

240,376

ARMCHAIR OR THE LIKE

Joseph E. Adkinson, 3807 Leland St.,
Chevy Chase, Md. 20015

Filed Apr. 23, 1974, Ser. No. 463,290

Term of patent 14 years

Int. Cl. D6—01

U.S. Cl. D6—68

FIG 1

FIG 2

FIG 3

FIG. 1 is a perspective view of an armchair showing my design;

FIG. 2 is a front elevational view showing the armchair of FIG. 1; and

FIG. 3 is a side elevational view of the armchair of FIGS. 1 and 2.

The back of the chair is plain and unornamented.

I claim:

The ornamental design for an armchair or the like, substantially as shown and described.
